UNITED STATES PATENT OFFICE.

CHARLES A. DANIELL, OF CHICAGO, ILLINOIS.

DESIGN FOR A MATCH-SAFE.

SPECIFICATION forming part of Design No. 26,577, dated February 2, 1897.

Application filed December 21, 1896. Serial No. 616,544. Term of patent 7 years.

To all whom it may concern:

- Be it known that I, CHARLES A. DANIELL, a citizen of the United States, and a resident of the city of Chicago, in the county of Cook and State of Illinois, have invented and produced a new and original Design for a Match-Safe, of which the following is a specification, reference being had to the accompanying drawings, forming a part thereof.
- 10 Figure I is a front view of a match-safe, showing my design. Fig. II is a back view thereof. Fig. III is a central vertical transverse section on the line III III, Figs. I and II.
- 15 The leading feature of my design consists in a match-safe representing an upright piano in outward appearance, having within it a

horizontal partition providing a hopper for holding matches.

The body of my match-safe has the conventionalized appearance of an ordinary upright piano. The upper portion is separated from the lower portion by a horizontal partition, thus providing a match-receptacle beneath the lid. 25

Having thus described my invention, the following is what I claim as new therein and desire to secure by Design Letters Patent:

The design for a match-safe; substantially as herein shown and described.

CHARLES A. DANIELL.
